UNITED STATES PATENT OFFICE.

FREDERICK CLARE, OF PRESTON, ONTARIO, CANADA.

RADIATOR.

1,007,643.

Specification of Letters Patent. Patented Oct. 31, 1911.

Application filed September 14, 1910. Serial No. 582,013.

To all whom it may concern:

Be it known that I, FREDERICK CLARE, a subject of the Dominion of Canada, and a resident of Preston, Province of Ontario, 5 Dominion of Canada, have invented certain new and useful Improvements in Radiators, of which the following is a specification, accompanied by drawings.

This invention relates to radiators, more particularly to steam radiators, although the invention may be used in any connection in which it is found to be applicable.

Difficulty has been experienced with radiators constructed of relatively thin material, 15 owing to the fact that the walls are apt to buckle due to the pressure from the inside or from the formation of a partial vacuum, and the objects of this invention are to improve upon the construction of such radiators and 20 enable the walls to be constructed of relatively thin material without the attendant disadvantages due to buckling and deformation, which tend to lessen the efficiency of the radiator.

25 The invention is particularly applicable to radiators having grooved or corrugated side members forming radiation chambers, and in accordance with this invention I provide reinforcing members between certain of 30 the opposing walls of the grooves or corrugations, either inside or outside of the radiator, or both, and at any desired vertical position with respect to the radiator. The reinforcing members may be of any suitable 35 or desired form and construction and serve to prevent deformation of the walls of the radiation chambers.

Further objects of the invention will hereinafter appear and to all of these ends the 40 invention consists of a radiator construction embodying the combinations of elements and arrangement of parts substantially as hereinafter fully described and claimed in this specification and shown in one of its 45 preferred embodiments in the accompanying drawings, in which—

Figure 1 is a side elevation of a radiator embodying the improvements; Fig. 2 is a horizontal sectional view of a radiator 50 partly broken away; Fig. 3 is a perspective view of one of the braces; and Fig. 4 is an enlarged detail sectional view on the line 2—2 of Fig. 2.

Referring to the drawings, the radiator 55 illustrating the preferred embodiment of the invention comprises a body portion prefer-

ably of relatively thin sheet metal. The side walls C and D of the body portion are provided with corrugations of sufficient depth to form radiation chambers having 60 efficient radiating surfaces. A and B represent the top and bottom members of the radiator which may be conveniently formed of cast metal. The body portion is fitted to the top and bottom members A and B, preferably by means of the rabbets 10 shown in Fig. 4. In the corrugated form of radiator shown, the corrugations extend inwardly leaving a central space 11 extending from top to bottom of the radiator, through which 70 the steam or other heating fluid may circulate.

I am not to be understood as limiting the invention to corrugated form of radiator construction, for the radiator may be formed 75 with grooves which are the equivalent of the spaces between the corrugations shown in the drawings, so that any form of side member may be used having corrugations therein.

In order to reinforce the substantially thin walls of the radiation chambers formed by the corrugations or grooves, I provide reinforcing means in the form of braces adapted to be placed between the opposing walls of 85 the corrugations and either inside or outside of the body portion of the radiator, or both inside and outside, as desired. I have illustrated a suitable form of bracing member at E, although I am not to be understood as 90 limiting myself to this particular form of reinforcing means. The braces E as shown in this instance may be formed of suitable material as cast or wrought iron and may be in the form of U-shaped members, the sides 95 12 of which are preferably connected by the transverse struts 13 and 14 of which there may be any desired number. If the bracing member E is formed of cast metal, the struts 13 and 14 are preferably cast integral therewith. The back 15 of the member E is preferably curved to conform to the inner curved portions of the corrugations.

The particular form of a bracing member E, I have shown by way of illustration is 105 placed at any desired height either inside or outside of the radiator and between the opposing surfaces of a corrugation or groove. In Fig. 1 the bracing members are shown at different heights on the outside of 110 the radiator and in Fig. 2 the bracing members are shown both inside and outside of

the radiator. The bracing members are located at such distances apart as are deemed necessary to effectually reinforce the entire structure. The reinforcing members are 5 preferably adapted to conform to the surfaces of the corrugations or grooves and may be placed in certain of the grooves or in at least some of the grooves, as desired.

It will be seen that the present invention 10 provides means whereby the radiator may be manufactured of extremely thin material and the strain on the walls of the chambers is resisted by the reinforcing members. The pressure from the inside is resisted by the 15 reinforcing members placed outside of the radiator. The walls of the chambers are prevented from buckling due to the formation of partial vacuum, by placing reinforcing members inside of the radiator.

20 As many changes could be made in the construction disclosed and many apparently widely different embodiments of the invention within the scope of the claims could be made without departing from the spirit or 25 scope thereof, it is understood and intended that all matter contained in the accompanying specification and drawings shall be interpreted as illustrative and not in a limiting sense.

30 I claim and desire to obtain by Letters Patent the following:

1. In a radiator, the combination with a side wall having vertical corrugations, of a plurality of independent reinforcing members 35 located in the corrugations and formed with portions fitting closely to the surfaces of the corrugations and conforming substantially to the shape of said corrugations.

2. In a radiator the combination with a 40 relatively thin grooved side wall, of a reinforcing member in the groove on the exterior adapted to conform to the surface of the groove, said reinforcing member being formed with a U-shaped section having the 45 opposite inner sides connected by a strut.

3. In a radiator the combination with a side wall having corrugations of a plurality of flat reinforcing members located in the corrugations and formed with portions fitting closely to the surface of the corrugations, said reinforcing members being 50 adapted to reinforce the side wall against internal pressure.

4. The combination in a radiator of top and bottom members, side walls having corrugations connected to said top and bottom members, a plurality of reinforcing members located in the corrugations, each of said reinforcing members being formed with a U-shaped section fitting closely to the corrugations and a strut connecting the inner sides 60 of the U-shaped section.

5. A radiator having side walls of relatively thin material formed with corrugations of sufficient depth to form radiation 65 chambers, and exterior reinforcing members arranged between the outer surfaces of the opposing walls of at least some of the chambers, said reinforcing members conforming substantially to the shape of said chambers. 70

6. A radiator having side walls of relatively thin material formed with chambers, and reinforcing means arranged between the opposing walls of certain of said chambers, said reinforcing means comprising members 75 having flat sides connected by struts.

7. In a radiator the combination of a side wall having corrugations, of a plurality of exterior and interior reinforcing members located in the corrugations and formed with 80 portions fitting closely to the surfaces of the corrugations and conforming thereto.

In testimony whereof I have signed this specification in the presence of two subscribing witnesses.

FREDERICK CLARE.
